METHOD OF AND MEANS FOR CONTROLLING TEMPERATURE

Application filed June 1, 1931. Serial No. 541,451.

This invention relates to the art of heat treating metals and the like. The invention includes both an improved method of heat treating thin sheets, more particularly steel sheets, and automatic means for regulating the temperature of a furnace in accordance with such method.

In the annealing of metal sheets and coiled strips, it has been found in practice that if the heat is turned on the furnace and the temperature raised too rapidly, warpage of the sheets or strips and burning of the edges thereof often occurs.

While, of course, these undesirable results can be avoided by raising the heat very slowly, it is obvious that, for the sake of economy, efficiency and rapid production, it is desirable to heat the furnace up just as quickly as possible and run it at as high a temperature as can be employed without damage to the charge.

I have discovered that the important factor in this connection is not so much the actual temperature or rate of rise of temperature of the furnace itself as it is the difference in temperature between the edges and the center of the charge.

I have found that objectionable warpage and burning of the edges of the sheets can be avoided by so regulating the heat input to the furnace that the temperature difference or gradient between the edges and center of the charge may approach but shall never exceed a certain predetermined maximum.

In the case of ordinary steels and other metals of relatively high heat conductivity, the temperature difference or gradient between the outside and the center of the charge is not so important as in the case of high silicon sheets, because the thermal conductivity of the latter is so low that heat is not readily transferred from one part of the charge to the other and consequently, a too rapid rise in temperature around the edges of the charge is very apt to result in burning and warpage.

I have also found that in the earlier stages of a heat, while the charge is relatively cool, the permissible temperature difference or gradient may be much higher, without damaging the charge, than it may be during the

later stages, when a relatively high temperature has been reached.

In carrying out my improved method in a manually controlled furnace, I employ a pair of pyrometers operated by thermocouples or other temperature responsive devices, located one at the edge and one near the center of the charge, and so regulate the supply of energy to the furnace that the difference in temperature between the inner and outer portions of the charge, as indicated by these pyrometers, does not exceed a predetermined amount, bearing in mind that the permissible temperature difference becomes less and less as the furnace heats up.

As regards automatic temperature regulating apparatus for performing the above described method, the primary object of the invention is the provision of means for controlling the rate of heat input to a furnace in such a way that a predetermined temperature difference or gradient between separated points of the charge, such as the edge and center thereof, will be maintained but not exceeded.

A further object is to provide automatic means for progressively reducing the permissible temperature difference or gradient as the temperature of the charge increases.

While capable of application with either fuel fired or electrically heated furnaces, my improved automatic controlling apparatus will be illustrated and described as applied to the latter type. Also, while my improved automatic controlling apparatus is particularly useful in connection with the annealing of metal sheets and the like, it, may, of course, be employed generally in connection with furnaces or heated chambers of other types.

In carrying out this part of the invention, I employ, as in the manual method, two thermocouples or other heat responsive devices located at separated points, and I control the heat input to the furnace by the differential action of these two devices. I may also superpose upon this control, the modifying action of a third temperature responsive device which varies the effect of the differential action of the other two devices in accordance

with the actual temperature existing in the furnace.

In order that the invention may be readily understood, reference is had to the accompanying drawings, forming part of this specification, and in which I have illustrated several examples of different ways in which the principles of the invention may be carried out, the drawings showing the invention as applied to an electrically heated furnace.

In these drawings:

Fig. 1 is a vertical sectional view through an annealing furnace, showing temperature responsive devices disposed therein in accordance with the invention;

Fig. 2 is a circuit diagram conventionally showing the furnace and temperature responsive devices as illustrated in Fig. 1, and also showing the automatic controlling means actuated by said devices;

Fig. 3 is a diagram similar to Fig. 2, but showing, in addition, manual means by which any desired predetermined temperature gradient may be selected, and also showing a third temperature responsive device for automatically reducing such gradient as the temperature of the furnace increases;

Fig. 4 is a similar diagram showing a somewhat different method by which the third temperature responsive device serves to modify the control exerted by the other two devices, and also illustrating a thermionic amplifier for increasing the sensitiveness of the control system; and

Fig. 5 is a conventional diagram illustrating in section a furnace such as shown in Fig. 1 and also showing still another method by which the differential action of the two temperature responsive devices may be caused to control the heat input.

Referring to Fig. 1, 1 designates a conventional annealing furnace of the hood type having on its inner walls the usual or any suitable electric heating elements or ribbons.

2. On the base or hearth 1^a of this furnace rests the charge 3 which may be a stack of steel sheets or the like.

Referring to Fig. 2, the heating elements 2 are connected through leads 4, power transformer 5, automatic switch 6, and leads 7 with the power supply line 8. The automatic switch 6, commonly known as a contactor, is operated by means of a solenoid 9, from which extend conductors 10 to the contacts of another automatic switch 11, operated by means of a solenoid 19. The switch 11 and solenoid 19 constitute a relay or auxiliary contactor.

The upper switch blade 11 is connected by means of wire 12 with one side of the power line and through a resistance 13 to a wire 14, which extends from one end of the solenoid winding 19 to a galvanometer contact 16, hereinafter more fully described. Associated with the contact 16 is a contact 15, and

this contact is connected by means of wires 17 and 18 with the other side of the solenoid 19.

Another pair of contacts 20 and 21 are disposed opposite the contacts 15 and 16, the contact 20 being connected with the wire 17 and the contact 21 being connected by a wire 22 with the other side of the power line and by wire 23 with the lower switch blade 11.

In order to maintain the solenoid 19 energized, a third switch blade 24 is provided, and this is connected by means of a wire 26 with the wire 22. A wire 25 also connects the contact of the switch blade 24 with the wire 18.

The control apparatus illustrated embodies a pyrometer or galvanometer 28 of the D'Arsonval type, having a movable coil to which is attached a pointer or arm 27 which serves to close the circuit between the contacts 15 and 16 on the one hand and the contacts 20 and 21 on the other hand, in accordance with its position. The movable coil of this galvanometer is connected by wires 29, 30 and 31, with the two temperature responsive devices or thermocouples 32 and 33. One of these thermocouples such as 32 is placed adjacent the center of the charge 3 and the other, such as 33, is placed adjacent the edge of such charge, as clearly shown in the drawings.

From an inspection of Fig. 1, it will be seen that I lead the wires 29, 30 and 31 into the furnace through specially formed passages in the base or hearth 1^a. Thus the use of the thermocouples 32 and 33 does not interfere with the free removal of the furnace hood.

As illustrated in Fig. 2, the positive sides of the two thermocouples are connected together by wire 30 and the negative sides are connected to wires 29 and 31 leading to the galvanometer or pyrometer, the thermocouples being thus opposed to each other.

The operation of the control apparatus, as shown in Figs. 1 and 2, will now be briefly described. Normally, when the furnace is cold, the galvanometer arm is in its left hand position, as shown in full lines in Fig. 2, so as to bridge the contacts 20 and 21, thus energizing the solenoid 19 of the relay or auxiliary contactor over a circuit including the resistance 13, solenoid 19, wire 18, contacts 20 and 21, and wire 22. Immediately that the solenoid 19 picks up its armature and closes the switch, a holding circuit is established through the solenoid 19 by way of wire 25, switch 24, and wire 26, independent of the contacts 20 and 21, so that the arm 27 may move away from these contacts without affecting the relay. Closure of the switch blades 11 establishes a circuit of wires 12, 10, 22 and 23, through solenoid 9 of the main contactor which thereupon closes and sup-

plies power to the heating element 2 of the furnace.

As the furnace heats up, it is obvious that the outer portions or edges of the charge, 5 being nearer the heating elements, will become hot before the temperature of the center of the charge has risen to any appreciable extent. Therefore, the thermocouple 33 will generate an electromotive force much greater 10 than that generated by the thermocouple 32, and, being connected in opposition, the thermocouple 33 will predominate and will cause a current to flow over the wires 30, 31, and 29, through the coil of the galvanometer, the 15 direction of this current being such as to cause the pointer or arm 27 to move toward the right. When the difference in temperature to which the thermocouples 32 and 33 are subjected at the center and edge of the 20 charge, respectively, reaches a predetermined amount, the current flowing through the wires 29 will be sufficient to move the arm or pointer 27 over against the contacts 15 and 16, as shown in dotted lines. When these 25 contacts are engaged by the arm, a circuit including these contacts and the wires 14, 17 and 18, and the coil 19, is closed, thus completely short circuiting the coil 19 and depriving it of current. Thereupon, the switch 30 blades 11 drop away from their contacts, as shown in dotted lines, thus deenergizing the solenoid 9 and opening the main contactor switch, cutting power off from the furnace.

Power will thus remain cut off until either 35 the outer portion of the charge has cooled down or the inner portion has heated up to such an extent that the resultant current, due to the differential action of the thermocouples, is insufficient to keep the arm 27 away 40 from the contacts 20 and 21. This arm, being biased toward these contacts, therefore comes into engagement with them again, thus again causing the relay 19 to become energized and power to be again supplied to the furnace.

45 From the foregoing, it will be seen that my improved control apparatus operates to cut the power off from the furnace whenever the temperature difference between the edge and center of the charge exceeds a predetermined 50 amount, and to turn the power on again, when this temperature difference or gradient has returned to a permissible figure.

Referring now to Fig. 3, I have illustrated 55 an arrangement in which the predetermined temperature gradient may be manually adjusted as desired and also in which automatic means are provided for decreasing this 60 gradient as the temperature of the furnace increases. In this figure, the same reference numerals designate the same parts as in Figs. 1 and 2, and it is unnecessary to repeat a description of the arrangement and operation of these parts. An alternative arrangement 65 as regards the arm 27 is, however, illustrated, in that the wire 18, instead of being

connected to two supplemental contacts 15 and 20, as in Fig. 2, is connected through a flexible lead directly to the arm 27. The electrical effect is, of course, identical, and the auxiliary contactor or relay is energized and de-energized by engagement of the arm 27 with the contacts 21 and 16, as before.

The movable coil of the galvanometer 28, however, instead of having both terminals connected directly with the thermocouples, 70 as in Fig. 2, has one terminal connected with the thermocouple 32, and the other terminal connected by a wire 38, to a movable contact 39, adjustable along a resistance 36, after the manner of a potentiometer. The other side of the thermocouple 32 is connected by a wire 34 with one side of the thermocouple 33, the other side of the latter being connected by a wire 35 with the resistance 36. It will thus be seen that the two thermocouples 32 and 33 are connected in a series circuit with the galvanometer coil and the resistance 36, the polarities of the two thermocouples being such that their voltages oppose or buck each other, as in Fig. 2.

A battery 42 has one terminal 40 connected by a wire 41 in such a way as to be adjustable along the resistance 36, and its other terminal is connected to a wire 43, the respective polarities of the battery and of the thermocouples being, as indicated, by the plus and minus signs on the drawings.

Assuming, for the moment, as might well be the case, that the wires 35 and 43 are directly connected, it will be seen that by virtue of the potential drop through the resistance 36, a certain voltage is impressed by the battery 42, upon the terminals of the galvanometer coil, and that this voltage may be adjusted to any desired value within the range of the instrument by shifting the contacts 39 and 40 along the resistance 36. Thus, when no voltage is being generated in the thermocouples 32 and 33, the current flowing through the galvanometer coil may be so adjusted that the biasing means of the instrument is just able to overcome the torque due to this current and maintain the arm 27 in its left hand position, it being understood that the current tends to move the arm 27 toward the right.

As the furnace heats up, a higher voltage is generated in the thermocouple 33 than in the thermocouple 32, and the former therefore predominates, and sets up an electromotive force in the same direction as that impressed by the battery 42, so that the current flowing through the galvanometer coil is to be increased. As the temperature rises, the current, due to the joint action of the battery 42 and the predominating thermocouple continues to increase until it becomes strong enough to move the arm 27 over against contact 16, whereupon power is cut off from the furnace, as above described.

As set forth in the specification I have found that the charge during the early stages of the heat will stand a much higher temperature gradient or difference between the edge and center portions thereof, than during later stages, and I therefore find it desirable to provide means for automatically reducing the permissible temperature gradient as the heat progresses. To this end, I have illustrated, in Fig. 3, a third temperature responsive device or thermocouple 47, and I connect this as by wires 46 with the movable coil of a galvanometer 45, having an arm or pointer 44. This arm is flexibly connected with the wire 43 leading to the battery 42.

I also arrange in cooperative relation with the arm 44 an arcuate series of contacts 48, between which are connected sections of resistance 49, the last contact being connected to the wire 35.

When the furnace is cold, the arm 44 is in its upper extreme position, as shown in dotted lines, so that the entire resistance 49 is included between the wires 43 and 35 and is in series with the resistance 36. Thus, it will be understood that the adjustment of the contacts 39 and 40, to bring the arm 27 to its desired initial position, is made with the resistance 49 in circuit. As the furnace heats up, an electromotive force is generated in the thermocouple 47 and this causes a current to flow through the coil of galvanometer 45 in such a direction as to tend to move the arm 44 downwardly to some such position as is shown in full lines. Thus, the hotter the furnace becomes, the further the arm 44 moves and the more the resistance 49 is cut out of circuit. Other factors remaining constant, it will be seen that the cutting out of the resistance 49 tends to increase the current flowing from the battery 42 through the coil of galvanometer 28, so that as more and more of the resistance 49 is cut out, less and less additional electromotive force is required to be impressed upon the circuit 29, 38, in order to move the arm 27 into engagement with the contact 16. It is therefore clear that as the furnace heats up, and as the thermocouple 47 is subjected to progressively higher temperatures, the possible temperature difference or gradient between the thermocouples 32 and 33, before the power is cut off, progressively decreases. For example, during the early stages of a heat, a temperature difference of three or four hundred degrees may be permitted, while after a critical temperature has been reached, this is automatically reduced to, say, one hundred degrees, in order to prevent burning or warping of the sheets constituting the charge.

While, for the sake of simplicity and clearness, I have illustrated the arm 44 as moving over the contacts 48, it will be understood that in practice, a more delicate and complicated arrangement is necessary, because the

currents generated by the thermocouple 47 are too minute to actually operate a rheostat as shown. The drawings, however, serve to illustrate the principle and the necessary changes will be readily understood by those skilled in the art.

While Fig. 3 shows both manual and automatic means for varying the gradient or temperature difference between the two portions of the charge, it will, of course, be understood that the manual adjusting means is capable of use independent of the automatic means embodying the galvanometer 45, since, as above explained, the wires 35 and 43 may be directly connected together, and the galvanometer 45 and its related parts omitted.

In Fig. 4, I have illustrated a somewhat modified arrangement in which a thermionic amplifier and two auxiliary contactors or relays are employed, but in which the corresponding parts have been given the same reference characters as in the preceding figures. In this figure, the wire 30 connects the positive sides of the two thermocouples 32 and 33, as in Fig. 2, and the wire 31, leading from the negative side of one of the thermocouples is connected to the grid of an amplifier tube 53. The filament of the tube is connected with an A-battery 54, and with the wire 30^a connecting with the negative side of the other thermocouple. In the plate circuit of the tube is connected a B-battery and a high resistance 56 across which is shunted, by means of wires 29, the movable coil of the galvanometer 28.

A transformer 5^a is shown as having its primary windings connected by wires 50 with leads 8^a extending from the power line 8, and its secondary windings, as connected, one to the wire 12 including the resistance 13 and the other to the wire 14 extending to the contact 16.

The galvanometer 28 is controlled by the differential action of the two opposed thermocouples 32 and 33, as before, operating in this case through the amplifier tube 53 in a well known manner.

It is desirable, in some cases, instead of providing means for varying the permissible temperature gradient as the furnace heats up, as in Fig. 3, to provide means for preventing the temperature of the furnace from exceeding a predetermined value. This, I have illustrated in Fig. 4, and I have shown a third temperature responsive device or thermocouple 47 for this purpose. In carrying out this feature of the invention, I provide an additional galvanometer or pyrometer 28^a having an arm 27^a, which by means of contacts 21^a and 16^a, controls the energization of the coil 19^a of a second auxiliary contactor or relay. Current is supplied to this control apparatus by means of a transformer 5^a having its primary winding connected by wires 50^a with the leads 8^a and its secondary wind-

ing connected at one side to the wire 12^a including the resistance 13^a, and at the other side to the wire 14^a extending to the contact 16^a.

- 5 The solenoid 9 of the main contactor is connected by a wire 10' with one power lead and by a wire 10 with the switch 11 of relay 19. From this switch extends a wire 51 to one side of the switch 11^a of the relay 19^a, the other side of this switch being connected by a wire 52 with the other power lead; thus the circuit of the main contactor 9 is controlled jointly by the two relay switches 11 and 11^a in series.
- 10 15 The galvanometer 28^a is controlled by the thermocouple 47, as illustrated in the following manner. One side of the thermocouple 47 is connected by wire 29^a to one side of the galvanometer coil and the other side of the thermocouple 47 is connected by a wire 57 to a terminal 57^a which engages a point between two of the arms of a Wheatstone bridge arrangement 58, the opposite point of the bridge being connected by a wire 38^a with the other side of the galvanometer coil. The other two points of the bridge are connected to the opposite poles of a battery 59, an adjustable resistance device 60, 61 being included in this connection. It will be understood 20 without further discussion that the Wheatstone bridge arrangement illustrated and described is for the purpose of permitting manual adjustment and making it possible to set the galvanometer 28^a so that the thermocouple 47 will cause the relay 19^a to be energized and the power shut off from the furnace when the temperature has reached 25 any desired predetermined value.
- 30 35 Thus, in the arrangement shown in Fig. 4, power will be shut off from the furnace either when the temperature difference or gradient between the edge and center of the charge reaches a certain predetermined amount, or when the furnace itself attains a predetermined temperature. Thus, damage 40 to the charge is prevented.

It will be understood that the third temperature responsive device 47 may be located at any desired point so as to respond either 45 to the heat of the furnace itself or of the charge.

50 Referring finally to Fig. 5, I have illustrated still another method in which the differential action of two temperature responsive devices may be caused to control the power input to a furnace. In this figure, I have illustrated the same furnace, the same thermocouples, and the same main and auxiliary contactors as before. The means for 55 controlling the relay or auxiliary contactor, however, in this case, comprise a pair of galvanometers 64 and 65, having their movable coils mechanically connected, as for example, mounted upon the same shaft 66. The thermocouple 32 is connected by wires 62 directly

60 with the movable coil of one galvanometer while the thermocouple 33 is connected by wires 63 with the movable coil of the other galvanometer, it being understood that the direction of current flow from the thermocouples in these two circuits is such as to tend to move the shaft 66 in opposite directions. The shaft 66 carries a contact arm 67, arranged to vibrate between the two contacts 16 and 21, as before, this arm 67 being connected through the shaft 66 with the wire 18, as in Fig. 3. The arrangement is such that when the current generated in the thermocouple 33, due to its temperature, is high enough to produce the torque necessary to overcome that produced by the lesser current generated in the thermocouple 32, due to the lower temperature of the latter, the arm 67 will be moved into engagement with the contact 16 and the power thus shut off from the furnace.

65 What I claim is:

1. In the heat treatment of a furnace charge the method of heating which comprises applying heat to the furnace to progressively raise its temperature, and so regulating the heat input that the temperature difference between two separate points of the charge approaches but does not exceed a predetermined amount.

90 2. In the heat treatment of a pack of metal sheets the method of heating which comprises gradually applying heat thereto and so regulating the rate of application that the difference in temperature between the edges and center of the pack approaches but never exceeds a predetermined amount.

95 3. In the annealing of a mass of metal the method of heating which comprises applying heat thereto to progressively raise its temperature, and so regulating the rate of application that the temperature gradient between two different portions thereof shall approach but not exceed a predetermined maximum during one stage, and shall not exceed a lesser amount during another stage.

100 110 4. In a temperature regulator for annealing furnaces, means for heating the charge in the furnace, a plurality of temperature responsive devices located adjacent different portions of the charge, and automatic means controlled jointly by said devices for preventing the temperature gradient between said portions of the charge from exceeding a predetermined amount during a part of the operation, and from exceeding a different predetermined amount during another part of the operation.

115 120 5. In a temperature regulator for furnaces, the combination with a furnace, and heating means therefor, of a plurality of temperature responsive devices located at different points in the furnace, and means controlled by said devices for preventing the temperature gradient between two separated points of the furnace from exceeding a pre-

determined amount during one temperature range, and from exceeding a different predetermined amount during another temperature range.

5 6. In a temperature regulator for furnaces, the combination with a furnace, and heating means therefor, of automatic means for preventing the difference in temperature between two separated points of the furnace from exceeding a predetermined amount, and means controlled by the temperature of the furnace for automatically and progressively varying such predetermined difference.

7. In a temperature regulator for furnaces, 15 the combination with a furnace, and heating means therefor, of a plurality of temperature responsive devices in said furnace, means controlled by one of said devices for automatically shunting off said heating means when the 20 temperature of a given point of the furnace, exceeds a predetermined value, and means controlled by other of said devices for shutting off said heating means when the difference in temperature between two given points 25 in the furnace exceeds a predetermined amount.

8. In a temperature regulator for furnaces, the combination with a furnace, and heating means therefore, a pair of temperature responsive devices, means governed by the differential action of said devices for controlling said heating means, a third temperature responsive device, and means whereby said third device modifies the effect of the 5 differential action of said pair of devices on said controlling means.

9. In a temperature regulator for furnaces, the combination with a furnace, and means for progressively heating the same, of a plurality of temperature responsive devices in said furnace, and automatic means controlled jointly by said devices for continuously maintaining the difference in temperature between two separated points of the furnace substantially inversely proportional to the temperature of a certain selected part of the furnace.

10. In heat treating a metallic mass, the method of heating which comprises progressively applying heat to the mass, controlling 0 the application of heat in such manner that the difference in temperature between the edge and center of the mass shall not exceed a given maximum, and gradually lowering the value of such difference as the temperature of the mass rises.

11. In heat treating a metallic mass, the method of heating which comprises progressively applying heat to the mass, and controlling such application of heat in accordance with the difference of temperature existing from time to time between the center and edge of the mass.

12. In the annealing of a pack of metal sheets, the method of heating which comprises applying heat thereto adjacent the edges of

said sheets, and so controlling the application of heat that the difference in temperature between said edges and the central portion of the pack shall at no time exceed a predetermined maximum.

13. In the heat treatment of sheets of metal of relatively low thermal conductivity, the method of preventing warpage and burning thereof which comprises assembling the sheets into a pack, applying heat to the edges of the sheets, and so governing the rate of heating that the difference in temperature between such edges and a point in the interior of the pack shall not exceed a predetermined amount.

14. In a temperature regulator for furnaces, the combination with a furnace, and means for supplying heat thereto, of a plurality of temperature responsive devices in said furnace, means controlled by one of said devices for preventing the temperature of a given point of the furnace from exceeding a predetermined value, and means controlled by other of said devices for preventing the difference in temperature between two given points in the furnace from exceeding a predetermined amount.

In testimony whereof I affix my signature.

GEORGE L. SIMPSON.
